UNITED STATES PATENT OFFICE.

CHARLES PURRINGTON, OF PEQUABUCK, CONNECTICUT.

BLIND OR SHUTTER HINGE.

No. 806,364.

Specification of Letters Patent.

Patented Dec. 5, 1905.

Application filed December 28, 1904. Serial No. 238,610.

To all whom it may concern:

Be it known that I, CHARLES PURRINGTON, a citizen of the United States, residing at Pequabuck, county of Litchfield, State of Connecticut, have invented certain new and useful Improvements in Blind or Shutter Hinges, of which the following is a specification.

My invention relates to improvements in blind or shutter hinges; and the objects of my improvement are simplicity and economy in construction and efficiency in use, especially with reference to a good hinge that will permit the blind to be readily removed.

In the accompanying drawings, Figure 1 is a front elevation of my hinge. Fig. 2 is a plan view of the same. Fig. 3 is a side elevation as viewed from the right-hand side of Fig. 1. In each of the said three figures the hinge is illustrated in its closed position—that is, the position which it will have in use when the blind is closed. Fig. 4 is a broken side elevation of the same as viewed from the left-hand side and with the swinging leaf turned back into a position to bring the blind approximately at an angle of forty-five degrees to the side of the house. Fig. 5 is a sectional plan view of the same with the plunger keyed back and the swinging leaf represented by full lines in position for detachment and by broken lines in the position shown in Fig. 4. Fig. 6 is a broken plan view of one of the half-sockets of the house member of my hinge.

The house member of my hinge is formed of two half-sockets 5 6, having hinge-lugs 14 at their outer ends, each formed with open pintle-receiving pockets 7, Fig. 6, while the main portion of the said sockets are designed to receive and hold the plunger 8 and its spring 9. These half-sockets may be held together and secured to the building in any ordinary manner; but I prefer to employ lugs 10 on the half-socket 5 to embrace the half-socket 6 at its outer end and hold the two together, while the other end of the half-socket 5 is provided with a rivet-like stud 11, that enters a perforation 12 in the half-socket 6 and which lug may be hammered down to hold the two half-sockets together. The two half-sockets form a cylindrical case adapted to be received in a hole made by a suitable boring-tool, and I also prefer to employ a fastening-plate 13, provided with screw-holes and arranged to encircle the case toward its outer end, as shown. A case having hinge-lugs at its outer end and inclosing a spring-pressed plunger for acting on holding-faces

of a companion hinge member is old and is hereby disclaimed.

In my hinge I make a recess in the edge of each of the hinge-lugs 14 on the blind side, so as to form the key-holding shoulders 15, that face toward the outer end of the plunger a little to one side thereof, and I widen the plunger at the corner adjacent to these shoulders, as shown at the left-hand outer corner of the plunger in Fig. 5, whereby when the plunger is forced back against the power of the spring it may be held in its forced-back position by inserting a proper key 16, Fig. 5, which key may be an ordinary cut nail or similar object.

By making the key-seat shoulders to one side of a vertical plane extending longitudinally through the case and axis of the hinge I am enabled to pass the key wholly across the front end of the plunger and have it bear on the case at opposite sides of the plunger, so as to hold the plunger firmly and closely to its extreme inward position.

The companion hinge member of my hinge consists of a hinge-lug 17, having three holding-faces 18, 19, and 20, two pintle-trunnions 21, and a suitable leaf 22 or other provision for securing the hinge-lug 17 to the blind. The hinge-lug 17 is of a thickness to be received in the space between the two hinge-lugs 14 of the companion member, while its trunnions are received and centered in the pintle-receiving pockets 7. The outer edge of the plunger 8 is rounded in a direction transversely to its broad sides, and the main portions of the holding-faces of the hinge-lug 17 are grooved to fit the said rounded edge, as shown. The action of the spring-plunger on the holding-faces of the hinge-lug 17 confines the trunnions of the said lugs within the pockets 6 of the hinge-lugs 14, while the rounded edge of the plunger and grooved holding-faces assist in holding the parts against accidental displacement. The general action of the plunger and holding-faces is the same as in prior hinges of this class.

In use both blind-hinges may be of my construction; but only one holding-hinge on a blind is necessary, and thus I prefer to use my hinge as the lower hinge on the blind, in connection with any ordinary loose-joint hinge for the upper hinge of the blind. In case it is desired to remove the blind it is swung open far enough to bring the hinge-lug 17 into the position shown in Fig. 4 and into the position indicated by broken lines in Fig. 5, in which position the plunger is forced back

against the power of its spring. The corner between the holding-faces 19 and 20 is made a little longer than the corner between the holding-faces 18 and 19, so as to force the 5 plunger back to a greater extent. When the plunger is thus forced back, there is a clear open space between the shoulders 15 and the confronting corner of the plunger 8, so that a key 16 may be inserted to hold the plunger 10 back, as shown in Fig. 5. The hinge-lug 17 may then be turned into a position to bring its holding-face 20 substantially parallel to the end of the plunger 8, and then the said face may be moved up against the held-back 15 plunger, as shown by the full lines in Fig. 5. The trunnions 21 of the said hinge-lug 17 will then be withdrawn from the centering portion of the pintle-pocket into a position in front of the side openings, so that the said lug may 20 be wholly disconnected by moving it bodily to the right. It is apparent that some changes from the specific construction herein disclosed may be made, and therefore I do not wish to be understood as limiting myself to the precise 25 form of construction shown and described, but desire the liberty to make such changes in working my invention as may fairly come within the spirit and scope of the same.

30 I claim as my invention—

1. In a blind or shutter hinge, the combination of a case having hinge-lugs, open pintle-receiving pockets, and two key-seat shoulders formed by open recesses in the side edges of 35 the said lugs and located to one side of a plane extending vertically along the axis of the

hinge and horizontally along the length of the case, with a spring-pressed plunger having a flattened head provided with a laterally-projecting corner facing the space between 40 the said key-seat shoulders and correspondingly located with reference to the said case and axis of the hinge, and a companion hinge-lug pivoted in the said lugs of the said case, for being engaged by the said plunger, the 45 whole being combined and arranged for inserting a single key in the space between the said two shoulders and projecting corner, with the said key spanning the space between the 50 said shoulders when the said plunger and the said companion hinge-lug are in engagement with each other.

2. In a blind or shutter hinge, the combination of the case having a pair of hinge-lugs and open pintle-receiving pockets in the confronting faces of the said lugs with a spring-pressed plunger mounted to slide within the said case and present its end face to the space between the said lugs, the said end face being rounded transversely to its broad sides, 60 and a companion hinge-lug having trunnions for being received in the said pockets and holding-faces with grooves that are fitted to the said rounded end face of the said plunger and extend along the edges of the said holding-faces transversely to the axis of the trunnions.

CHARLES PURRINGTON.
